SPRING-BALANCED HINGED STEP FOR CARS.

1,182,563.

Specification of Letters Patent.

Patented May 9, 1916.

Application filed October 2, 1914. Serial No. 864,698.

To all whom it may concern:

Be it known that we, FREDERIC W. HILD, FRANK P. MAIZE, and WILLIAM LEWIS COOP, citizens of the United States, and residents, respectively, of the city of Portland, county of Multnomah, State of Oregon, have invented a certain new and useful Improvement in Spring-Balanced Hinged Steps for Cars, of which the following is a specification.

Our invention relates to the hinged step of the spring-balanced type frequently used on street railway and interurban cars.

In the spring-balanced steps heretofore commonly used the cooperating devices are so arranged that the springs are in action in all positions of the step; consequently when the step is in its down or service position it is not held firmly in place, and every time it is stepped upon an annoying rattling sound is caused. To remove such annoyance is the object of our invention.

Our invention, may in a general way, be described as consisting in the combination with a car of a step pivoted on a horizontal axis, and means for balancing the step on its pivotal axis in all positions except its down position, said balancing means being arranged to be rendered inactive by the placing of the step in its down position.

In the accompanying drawings: Figure 1 is a sectional elevation of a portion of the entrance of a street-car, showing our improved spring-balanced step in its down or service position, and the broken lines show the same in its up or inactive position; the pieces horizontally aligned opposite Fig. 2 illustrate details of construction; and Fig. 3 is a view similar to Fig. 1, showing our invention applied to a single step.

The floor of the car, at the entrance, is indicated by *a*, and one of the side sills by *b*, the latter having on its bottom an abutment piece *c*, which serves as a stop. The step is hinged on a shaft *d*, suspended from the sill *b* of the car by any convenient means, not shown. The step *e* comprises two treads *e'*, *e''*, and a stop lug *e³*, which, when the step is in its down position, abuts against the stop *c*. When the step is in its up position the toe *e⁴* of the tread *e'* will contact with the stop *c*, thereby limiting the counter-clockwise rotation of the step and holding the latter in its inactive position.

The countershaft *f* is rotatably supported

from the bottom of the car by any convenient means, not shown, and has fixed on it a lever-arm *f'*, connected to a pin *g* on the step *e* by a link *h*. The pin *g* is located relatively to the step shaft *d* for giving good leverage. The countershaft *f* has mounted on it a fixed bevel-gear *i*, in mesh with a bevel-gear *j*, fixed on a vertical shaft *k*, which extends up above the motorman's platform and is provided with an operating handle *m*.

Bolted to the car bottom, *a*, is a hanger *n*, to which is pivoted the head *o*, affixed on one end of the spring element by which the step *e* is balanced as soon as slightly lifted. As shown in Fig. 1, this spring element comprises a tube *p*, threaded on both ends. See detail thereof in pieces shown in Fig. 2. One end of this tube is screwed into the head *o* which is provided with a perforated ear. The tube *p* is made with longitudinal slots *q*, and on its ends are threaded lock-nuts *r*, *s*. A rod *t* telescopes in the tube *p*, and a loose collar or sleeve *u*, sliding on the tube *p*, is fastened to the rod *t* by a pin *u'* extending through the slots *q*. The outer end of the rod *t* is pivotally connected by a pin *v* to the step *e*, and said rod end is made with a curved offset *t'*, so as to pass over the part of the step through which the shaft *d* passes. Coil-springs *w* and *x* are mounted on the tube *p*, the spring *w* being confined between the lock-nuts *r* and the collar *u*, and the spring *x* being confined between the collar *u* and lock-nuts *s*.

The power of the spring element is arranged relatively to the weight of the step so that the latter will be balanced or poised in every position except in its down position, that is to say, when the step is placed in service; and when so arranged its own weight will keep it in place and restrain vertical oscillation.

In the construction shown in Fig. 3, the step *y*, pivoting on the shaft *d'*, has only one tread, and has on its rear side a lever arm *y'*. A stop *z* is provided to limit the rotation of the step in both directions. The spring element is connected at one end to the hanger *n'*, pendent from the car floor and to the lever arm *y'* of the step. The spring-element comprises a rod *2* fastened to the head *o'* by the pin *3*. On the rod *2* slides a threaded sleeve *4*, and a collar *5* is threaded on said sleeve. A lock-nut *6* serves

to hold the collar 5 in fixed position on the sleeve 4. The collar 5 has an ear connected by the pin 7 with the lever arm y' of the step. A coil spring 8 is mounted on the rod 2 and is confined between the upper end of the sleeve 4 and the head o' . On the shaft d' of the step y is a fixed lever arm y^2 to which the link h' is pivoted; and the link h' is connected to the arm f' of the shaft f , which is rotated by the vertical shaft k and bevel gears i and j ; these devices corresponding to similar operating means shown in Fig. 1.

From the foregoing description it will now be seen that the step is so poised and controlled by the spring element that when the step is in its down position the balancing power of the spring action will be partially neutralized; in other words by placing the step to remain in its down position, the devices are so arranged that the weight of the step overcomes the pulling action of the spring. But when the step is slightly lifted the spring element will be thrown into action and aid in lifting the step, in so doing minimizing the work required in throwing the step in its inactive or uplifted position.

We claim:

- 30 1. A spring balanced step comprising a step pivoted on a horizontal axis, a stop for the step when in its down position, means for balancing the step on its pivotal axis in all positions except its down position, said means being adapted to have their balancing action overcome, by the placing of the step in its down position; and means for rotating the step on its pivotal axis.
- 40 2. In a spring balanced step the combination of a step pivoted on a horizontal axis, and a spring element controlling the step and operating to hold the same in poise on its pivotal axis in all positions except its down position.
- 45 3. In a spring balanced step the combination of a step pivoted on a horizontal axis, a spring element controlling the step, the power of the spring element being made relative to the weight of the step, and the spring element being connected to the step relatively to the latter's pivotal axis, so that the spring element will be partially neutralized by the placing of the step in its down position.
- 55 4. A spring balanced step comprising a step pivoted on a horizontal axis, a stop for the step when in its down position, a

spring element controlling the step, the power of the spring element being made relative to the weight of the step, and the 60 spring element being connected to the step relatively to the latter's pivotal axis, so that the spring element will be partially neutralized by the placing of the step in its down position, and means for rotating the 65 step on its pivotal axis.

5. A spring balanced step comprising a step pivoted on a horizontal axis, a spring element comprising a rod, a sleeve sliding on the rod, and a coil-spring controlling 70 the sleeve, the power of the spring being made relative to the weight of the step, one end of said spring element being pivoted to the support of the step, and the other end thereof being pivoted to the step 75 relatively to the latter's pivotal axis, and so that the power of the spring element will partially be neutralized by the placing of the step in its down position.

6. A spring balanced step comprising a 80 step pivoted on a horizontal axis, a spring element comprising a rod, a sleeve sliding on the rod, and a coil-spring controlling the sleeve, the power of the spring being made relative to the weight of the step; one end 85 of said spring element being pivoted to the support of the step, and the other end thereof being pivoted to the step relatively to the latter's pivotal axis, and so that the power of the spring element will be partially neutralized by the placing of the step in its 90 down position, and means for rotating the step on its pivotal axis.

7. A spring balanced step comprising a 95 step pivoted on a horizontal axis, a stop for the step when in its down position, a spring element comprising a rod, a sleeve sliding on the rod, and a coil-spring controlling the sleeve, the power of the spring being made relative to the weight of the 100 step, one end of said spring element being pivoted to the support of the step, and the other end thereof being pivoted to the step relatively to the latter's pivotal axis, and so that the power of the spring element will 105 be partially neutralized by the placing of the step in its down position, and means for rotating the step on its pivotal axis.
